TOOL GRINDING MACHINE

John W. Rouse, Little Falls, N. Y., and William D. Moore, Kansas City, Mo., assignors to Remington Arms Company, Inc., Bridgeport, Conn., a corporation of Delaware

Application April 7, 1944, Serial No. 529,910

7 Claims. (Cl. 125—11)

1

This invention relates to a profile grinding machine including means to support the work and means to true a profile grinding wheel by adjusting the truing elements in accordance with a gauge held in the work support. It is particularly adaptable for the production of profile cutting tools such as used for turning the head of the conventional cartridge case but is not limited thereto. The shapes of the tools for the cutting of the groove near the head of a cartridge must be accurately produced. These dimensions and angles vary for the different sizes and types of ammunition so that the angles and size of the wheel must be changed in accordance with the head turning tool to be made. These and other objects of the invention will become apparent from the accompanying description and drawings.

In the drawings—

Fig. 1 is a side elevation with some of the parts broken away and others partially in section, parts of a conventional grinding machine being shown.

Fig. 2 is a sectional view looking in the direction 2—2 of Fig. 1.

Fig. 3 is an end view looking in the direction 3—3 of Fig. 1, showing the gauge bar in place, the grinding wheel being omitted.

Fig. 4 is a side view of one form of gauge bar.

Fig. 5 is an end view looking from the left of Fig. 4.

Fig. 6 is an end view looking from the right of Fig. 4.

Fig. 7 is a side view of one form of head turning tool.

Fig. 8 is an enlarged end view of a head turning tool such as shown in Fig. 7, the relation thereof to a cartridge case being shown.

Fig. 9 is an end view looking from the right of Fig. 1, showing the gauge bar located in the work-holding slot.

Fig. 10 is a fragmentary view of a head turning tool in place in the work-holding groove with the wheel in contact therewith.

The work-holding support and wheel truing device are shown in use on a conventional magnetic chuck type grinding machine. This may be of the variety wherein the magnetic chuck table is reciprocated longitudinally and the grinding wheel or the height of the chuck table is adjustable in order to obtain the proper spaced relation between the grinding wheel and the work on the table or the diamond-like truing tools.

Referring to Figs. 7 and 8, a profile tool 20 for cutting the groove 21 in the end of a cartridge case 22 is shown. The cartridge case 22 is held

2

in a rotatable chuck of some description and the profile tool 20 is held in a suitable work support and advanced toward the work. The groove 23 must be very accurately cut into the tool in order to produce a correct groove in the cartridge case, said groove being critical, inasmuch as the cartridge case must feed properly into the mechanisms of the gun, for which it is designed. The grinding wheel 24 may be of any conventional type and material. A support 25 is provided, said support being made in a conventional manner of alternate ferrous and non-ferrous plates, said plates being held together by the assembly bolts 26. This construction is used for increasing the efficiency of the magnetic chuck but it is to be understood that other kinds of material or designs can be used. A groove 27 is provided therein for supporting the work as shown in Fig. 10 or the gauge bar as shown in Figs. 3 and 9.

20 In general, the wheel is profiled to the desired angles and face widths by means of diamond truing elements, said truing elements being set by means of the gauge bar (Figs. 4, 5 and 6). Thereafter, a blank bar or bar with the desired 25 exterior contour is placed in the groove 27 and the groove 23 cut therein (Fig. 10).

The tool truing elements will first be described. These are shown at 28, 29 and 30. It is to be understood, of course, that the truing elements 30 28, 29 and 30 may be of the conventional diamond type or other similar material and the expression “diamond-like” means a truing element suitable for truing the grinding wheel to be used. Truing elements 28 and 29 are used for truing the side surfaces 31 and 32 of the wheel and truing element 30 is used for cutting or truing the edge surface 33 of the grinding wheel. The truing elements 28, 29 and 30 are adjustably mounted on their carriers by means of nuts 34 in some suitable manner. The carriers 44, 45 and 48 for the truing elements have a suitable groove therein which may be of the type such as shown at 36 of Fig. 1, there being a corresponding tongue 37 on the supporting brackets 38. The bracket 38 may 45 be adjustably connected (not shown) to the base 41 (Fig. 1) in any conventional manner such as by a nut and bolt so as to allow a change to be made in the path of travel of the truing element carrier. When the grinding wheel is reciprocated adjacent to truing elements 28 and 29, said elements are reciprocated relative to the face of the wheel by means of a rocking motion of lever 39 (Fig. 3), said lever being pivoted at 40 to the base 41. Base 41 is attached by bolts or other 50 means to the laminated work support 25. The 55

base also may be integral therewith. Links 42 and 43 are pivotally attached to the truing element carriers 44 and 45, said links being also pivotally mounted at 46 and 47 to the lever 39. It is evident, therefore, that with a rocking motion of arm 39, the carriers 44 and 45 will be reciprocated on the tongue and groove mountings of their respective brackets 38 and thus be carried across the face of the grinding wheel to dress the same. Similarly, movement of lever 46' (Fig. 2), pivoted at 47 on frame 41, will cause reciprocation of the truing element carrier 48 and thus dress the surface 33 of the grinding wheel. Link 49 is pivotally mounted to lever 46' at 50 and to the carrier at 51. The diamonds are predeterminedly set in a manner which will be described presently.

In order to set the truing elements, the gauge bar shown in Figs. 4, 5, and 6 is placed in the work-holding groove 27, the diamond truing elements appropriately being located in a prolongation of said groove. The gauge bar shown has three sets of gauging surfaces thereon, one set for caliber .50, one set for caliber .30 carbine, and one set for caliber .30 '06. It is evident that a single set may be used or that other combinations may be placed on the gauge bar. The gauge bar has a central portion 52 which rests in the work and gauge holding groove 27 of the work support 25. The angles of this groove are selected in accordance with the work to be ground. For a head turning tool, the bottom surface 53 (Fig. 8) of the groove in the head turning tool is parallel with the bottom face 58 of the tool so that the grinding surface 33 of the wheel is parallel with the surface 54 of the groove in work support 25. A cut back portion 68' may be provided so as to allow for clearance of element 30 when the bar is being used to set elements 28 and 29.

Surfaces 55, 56 and 57 are for the purpose of setting the diamond 30 which dresses the face 33 of the grinding wheel. Faces 55, 56 and 57 are spaced above surface 52 the depth from the bottom of groove 53 of the tool to the lower face 58 thereof. Corresponding gauge surfaces 60 and 60' (caliber .50), 61 and 61' (caliber .30 carbine), 62 and 62' (caliber .30 '06), are located on the opposite end of the gauge bar, these surfaces being designed for setting diamonds 28 and 29 to cut side faces 31 and 32 of the grinding wheel.

Referring to Fig. 3, the gauge bar 63 is shown located in the groove in the work support with the diamonds adjacent the desired surfaces and arranged so that they can be brought against the surfaces thereof or a feeler of predetermined thickness placed between the diamond and the surface to prevent scratching thereof. A set of surfaces is selected for the head turning tool to be made. In order to set the diamond 30, the gauge bar 63 is reversed in the groove 27 so that the appropriate surface 55, 56 or 57 is over the diamond 30, at which time the diamond may be adjusted by means of nut 34 to touch the gauge surface or to touch feelers thereon. After the diamond has been set, the side faces 31 and 32 of the wheel are first surfaced to the correct type of face desired.

The usual grinding machine of the type shown has a dial for raising and lowering the chuck table with a depth indicator thereon. The reading on the indicator is noted at the time when the side surfaces are in their correct state. The surface 33 is then dressed by means of the diamond or truing element 30, the indicator for the table being brought to the same figure as when the

side surfaces of the wheel were dressed. In this manner, the correct angles and sizes of surfaces are obtained on the wheel.

Inasmuch as the diamonds, when adjusted by the gauge, have the correct height above the surface of the work supporting groove 27, a piece of tool stock which has had its other surfaces brought to their correct dimensions, may be placed in the groove and groove 53 cut therein, bringing the table indicator for the final cut to the same indication as when the wheel was dressed. For fine work, the wheel can be dressed before the final cut is made, the new depth indication being noted and the wheel brought to the same depth indication for the final cut for the groove 53 in the head turning tool.

In these and the setting operations the gauge bar or workpiece respectively is held in place by the action of the magnetic chuck, care being taken to wipe the bar or piece and groove 27 clean. It is apparent that other means than a magnetic chuck may be employed to hold the support.

The surfaces 55 and 60 defining the groove which runs the length of the gauge bar serve as vertical and horizontal gauging surfaces in order to position correctly the support on the magnetic chuck when the gauge bar is in place, the angles of these surfaces being so chosen in relation to the surfaces of the groove 27 as to be vertical and horizontal respectively.

Merely by way of example, for the caliber .30 '06, caliber .30 carbine, and caliber .50, the angle A (Fig. 8) is 45°. The angle B for these cartridges varies slightly but this is governed by the angle to which surface 67 is ground. The surface 54 makes an angle of 22½° with the horizontal, and surface 68 makes an angle of 67½° with the horizontal. These angles are merely by way of example and may be changed to suit the particular head turning tool or other tool being made. With the angle selected, the face 31 and 32 of the wheel will be substantially equiangular with the vertical as shown in Fig. 2. By using a groove which is horizontally located, as shown in Fig. 9, the tool and gauge will rest therein and initially be positioned by gravity. When the current is turned on for the magnetic chuck, the tendency will be for the tool to seat itself properly in the groove. For this reason, a V-shaped groove in the horizontal surfaces wherein the faces of the V make an angle with the vertical will be more efficient in positioning the gauge bar and tool in the work-holding support. It is to be understood, however, that the groove may take other forms than that shown.

What is claimed is:

1. In a profile grinding machine, a work and gauge holding device comprising a work-holding rest having a work and gauge holding surface thereon, a plurality of grinding wheel truing elements aligned with said work-holding surface and each slidably supported by said rest for truing a surface of a grinding wheel to a predetermined profile, said truing elements being individually adjustable to fit a gauge bar held on said work-holding surface.

2. In a profile grinding machine, a work and gauge holding support comprising a work-holding rest having a work and gauge holding groove therein, said support being adapted to be held by a magnetic chuck; a plurality of adjustable grinding wheel truing elements for each of the profile surfaces respectively of a grinding wheel; means held by said work and gauge support for movably

mounting each of said truing elements, said truing elements being adjustable to fit a gauge bar held in said groove; and means to reciprocate said truing element mountings for truing the faces of a grinding wheel brought in proximity thereto to a predetermined profile.

3. In a profile grinding machine, a work and gauge holding support comprising a work-holding rest having a work and gauge holding groove therein; a plurality of adjustable diamond-like wheel truing elements for each of the profile surfaces respectively of a grinding wheel; means held by said work and gauge support for movably supporting said truing elements for rectilinear movement parallel to said profile surfaces; and means for adjusting the height of said elements relative to said supports in accordance with a gauge bar held in said groove.

4. In a profile grinding machine, a work and gauge holding support comprising a work-holding rest having a work and gauge groove therein; a plurality of adjustable diamond-like wheel truing elements for each of the profile surfaces respectively of a grinding wheel; means held by said work and gauge support for movably supporting said truing elements for rectilinear movement parallel to said profile surfaces; means for adjusting the height of said elements relative to said supports in accordance with one set of several sets of gauging surfaces on a gauge bar held in said groove, each set having a surface at each end of said gauge bar.

5. In a profile grinding machine, a work and gauge holding support comprising a work-holding rest having a work and gauge-holding groove therein; not less than three diamond-like wheel truing elements for each of the profile surfaces respectively of a grinding wheel; means held by said work and gauge support for movably supporting said truing elements for rectilinear movement parallel to said profile surfaces; means to

reciprocate said truing element mountings, at least two of said mountings being connected together; means for adjusting the height of at least two of said truing elements in accordance with one of several sets of surfaces on a gauge bar held in said groove; and means for adjusting other of said truing elements in accordance with surfaces on another portion of said gauge bar held in said groove.

10 6. In a profile grinding machine, a work and gauge holding device comprising a work-holding rest having a work and gauge holding groove therein; a plurality of adjustable grinding wheel truing elements for each of the profile surfaces respectively of a grinding wheel; truing element mounting means held by said work-holding rest for movably supporting each of said truing elements, said truing elements being adjustable to fit a gauge bar held in said groove, said adjustment being such as to give the correct profile cut on the wheel to a piece of work in said groove; and means to reciprocate said truing element mountings for truing the faces of a grinding wheel brought in contact thereto to a predetermined profile.

20 7. In a profile grinding machine, a work and gauge holding support comprising a work rest having a V-shaped work and gauge holding groove in a horizontal portion thereof; a plurality of adjustable grinding wheel truing elements for each of the profile surfaces respectively of a grinding wheel; means held by said work and gauge support for movably mounting each of said truing elements, said truing elements being adjustable to fit a gauge bar held in said groove; and means to reciprocate said truing element mountings for truing the faces of a grinding wheel brought in proximity thereto to a predetermined profile.
